ABSTRACT: A system is disclosed for generating a matrix of data which relates to the formulation of animal feeds. The matrix is developed in a matrix register which is a logic array of component storage locations or registers for holding an organization of data relating to nutrients and ingredients. The specification of nutrients and ingredients for a desired feed is registered as two columns in the matrix register, from which the system operates to complete the entire matrix with information from an ingredient storage means which contains nutrient information on various specific ingredients.

MATRIX GENERATOR FOR USE IN SOLVING FEED FORMULATION PROBLEMS

BACKGROUND OF THE INVENTION

Linear programming affords an important tool for economic and business planning. The term refers to the methods used in formulating and solving a specific class of problems whereby it is desired to attain a maximum or a minimum quantity of some objective function, as cost, utilization, speed or the like. Generally, in solving these problems, a set of related linear equations are developed describing a physical situation and the attendant limitations that are involved. The equations are then solved, by various techniques, to provide the desired criteria for the objective function. In spite of the similarity of terms, linear programming has little connection with computer programming; however, linear programming problems may be programmed for solution on digital computers. For example, the so-called "simplex method" of solving linear-program problems might be accomplished by a digital computer.

In general, preliminary to solving a linear-programming problem, it is necessary to develop an array or matrix of data from which the linear equations are mechanically formulated. Conventionally, such matrices have been developed manually, requiring considerable time and effort and involving possibilities for error. For example, a matrix for use in the solution of linear-programming problems related to animal feed might involve an array of ingredients defining columns, with their component nutrients in orderly rows.

Conventionally, a nutritionist specifies the particular nutrients (as by percentage) for a desired animal feed, e.g., beef. Traditionally a variety of ingredients are also specified (some with limitations) for possible use in the feed. From such a specification, a matrix is developed for use in solving the linear-programming problem to attain the desired feed (specified nutrients) at the lowest practical cost. In general, the system hereof provides an effective and economical system for generating the requisite ingredient-nutrient matrix. The matrix is developed from one column containing the specifications in a matrix register, which column controls the operational steps of the entire system.

In the drawings which constitute a part of this specification, an exemplary embodiment demonstrating various objectives and features hereof is set forth, specifically:

FIG. 1 is a diagram illustrating a portion of a matrix as may be generated by the system hereof;

FIG. 2 is a block diagram illustrative of the general operation of the system hereof;

FIG. 3 is a diagram of a signal-represented word format utilized in the system hereof; and

FIG. 4 is a block diagram of a system constructed in accordance with the present invention.

DESCRIPTION OF THE ILLUSTRATIVE EMBODIMENT

As required, a detailed illustrative embodiment of the invention is disclosed herein. The embodiment merely exemplifies the invention which may, of course, be constructed in various other forms, some of which may be radically different from the disclosed illustrative embodiment. However, specific structural and functional details disclosed herein are merely representative and in that regard provide a basis for the claims herein which define the scope of the present invention.

In the growth and development of animals for human consumption, feeds are exceedingly important in relation to economy and proper development of the animal. The ingredients of a feed may constitute various feed components, providing the nutritional requirements are satisfied. That is, the nutritional requirements of a desired feed can be provided from a wide variety of possible formulations. The determination of the presently most economical ingredients for the desired feed may be the objective of a linear-programming problem; and as an interim matter, the generation of a linear-programming matrix is ordinarily necessary.

In the course of preparing feed for cattle, for example, it has been common practice in the past for a nutritionist to specify the nutritional values of a desired feed, as well as to place limitations (minimums, maximums or both) on certain component ingredients that might be used in formulating the feed. As indicated above, many formulas could satisfy the requirements of such a specification, using substantially different ingredients. Thus, a linear-programming problem is presented. That is, linear-programming techniques can be used to select the combination of ingredients which will most economically (in accordance with current prices) fulfill the nutritional specifications; and as a result, substantial savings will result in formulating the feed.

It has been previously proposed to solve such linear-programming problems by the use of digital computers and such techniques are well known in the prior art. However, in general, preliminarily, the data must be formed into a matrix that is provided to the computer. For example, assuming a somewhat simplified situation, a data matrix may be provided by the system hereof as set forth in FIG. 1.

Of course, the matrix may take various forms; however, it is generally an array of defined columns and rows. For example, rows specify the nutrients 1, 2 and so on for each of a plurality of potential ingredients A, B, C, D and so on, arranged in columns. In the simplified matrix shown in FIG. 1, the potential ingredients for the feed might be: (A) molasses, (B) barley, (C) fat, and (D) corn. The specified nutrients for the feed as present in each of the potential ingredients are then set forth in columns, e.g., (1) protein, (2) calcium, etc. The specification of the feed is set forth in the right-hand column under the heading "Formula Requirements." Considering FIG. 1 in further detail, the right-hand column associated with specific nutrients and ingredients specifies the formula. Specifically, as indicated the exemplary formulation is to have a minimum of 12 percent (1) protein, a minimum of 4 percent (2) calcium and so on.

As indicated above, having specified a feed, the next step involves generating the matrix (as explained) including the nutrient percentages set forth in the section M as indicated, for each of the potential ingredients. That operation has conventionally been performed manually, resulting in considerable effort as well as a substantial potential danger for error. In general, the system hereof affords a simplified, expeditious and economical means for generating the matrix M simply on the basis of the specification of the formulation's requirements. It is to be noted as a generality, that in accordance with the system hereof, in stating the feed requirements (specification) it is necessary to provide a minimum and/or a maximum requirement for each potential ingredient. That is, if the solution to the problem is to consider an ingredient, the ingredient (along with a minimum, a maximum or both therefor) must be provided in the right-hand column as registered in the matrix register of the system hereof.

Referring now to FIG. 2, the system hereof is depicted in conjunction with a total structure. Specifically, the system hereof is particularly directed to a matrix generator as represented by a block 10 which functions in conjunction with, and incorporates, an input 12 (for formula requirements) and a file 14 (for ingredient characteristics). That is, the matrix generator 10 receives the formulation requirements in a particular format from the input 12, then functions in cooperation with the ingredient characteristic file 14 to provide an output which may be directly supplied to a linear-program system 16 to solve the linear-program problem and provide the solution at an output unit 18.

As indicated above, previous linear-programming systems are well known in the prior art for use as the system 16 along with a satisfactory output 18. The portion of the system comprising the matrix generator 10 along with the input 12 and the ingredient characteristic file 14, are shown in considerable detail in FIG. 4 and will be considered below in relation thereto.

The solution to the problem, which solution is provided at the output 18 (FIG. 2), is in the form of an actual feed formulation. That is, the matrix, as illustrated in FIG. 1, would be utilized to develop the selected economical, practical formula. It is to be noted that although only a few representative ingredients are illustrated, the ingredients in a formula may well extend into 10's of numbers.

The placement of data into the matrix generator 10 requires the formulation of the data into a particular signal-represented word format. That word format is illustrated in FIG. 3 and will now be considered in detail. Of course, it is to be understood that the format utilized as well as the specific structural details hereof have a wide range of equivalent alternatives.

The data input word 5 supplied to the system hereof define the nutrients and ingredients which are registered at the right-hand side of the matrix and which specify: (1) the nutritional requirements of the formulation, and (2) the potential ingredients to be considered for use in the formulation (with limitations). In addition, the computer involved with solving the linear-programming problem will receive price information; however, such information is not a part of the matrix. Rather, the price information is simply provided to the linear-programming computer to specify the price for each of the potential ingredients in the formulation.

The input word for the system hereof as depicted in FIG. 3 consists of 15 binary bits. The first bit identifies the representation of the word as either a nutrient or an ingredient, i.e., a binary "one" indicates an ingredient while a binary "zero" indicates a nutrient.

The next six bits of the word identify a specific nutrient or ingredient in accordance with a preestablished code. In effect, these bits not only identify the nutrients and ingredients but additionally, the bits comprise an address for use in the system of FIG. 4 to obtain nutrient data for specific ingredients as described in detail below.

The next bit eighth of the word indicates whether the specified limitation is a "maximum" or a "minimum." Specifically, if the eighth bit is a "one" the nutrient or ingredient is specified as a minimum, while on the contrary, a "zero" binary bit indicates a maximum.

The last seven bits of the binary word specify the threshold value as a percentage. That is, these bits are coded to represent the threshold maximum or minimum as the case may be, straight binary numbers or any variation thereof.

The binary word as considered above with reference to FIG. 3 is developed in an input register 20 (upper right) as shown in FIG. 4. The input register 20 may receive the binary word by means of a keyboard (not shown) or from an external source as indicated by the input line 22; however, the specific source and formation of the signal-represented input code word is ancillary to the present invention.

The input register 20 receives code words as illustrated in FIG. 3, the last 14 bits of which are registered in the two right-hand columns 24 and 25 of a matrix register 26. The register 26 is fragmentarily shown as its size may vary widely depending upon the capacity of the system. However, in general the register must accommodate an array or matrix of similar, seven-bit numbers in rows equal to the total number of specified nutrients and ingredients, and columns sufficient to accommodate all of the potential ingredients, plus two (formula specifications). The storage elements in the matrix register 26 comprise individual registers which, as indicated, may be of seven binary bits capacity, all of which serve to register percentages, excepting those in the two columns 24 and 25 which register the codes for the nutrients and ingredients threshold percentages and the "maximum-minimum" bit.

As a preliminary consideration it is to be understood that, upon registration of the specified nutrients in the upper portion of the right side of the matrix register 26 and the specified ingredients below them, (in the lower portion of the matrix register 26) those registers control the operation of the system to develop percentage values in all of the other seven-bit component registers of the matrix register 26, to complete the data

matrix as desired. When the matrix is complete, the left-hand column of the matrix register 26 contains the percentage of nutrients present in the ingredient 14. Specifically, for example, assuming that the ingredient 14 is "rolled barley," the

5 contents of the registers in the left-hand column would indicate the presence of the nutrients N1, N2, N3 and N4 in percentages. Pursuing the example further, if N1 represents "protein," N2 is "fat," N3 is "fiber," and N4 is "calcium," the percentages thereof present in rolled barley would appear in 10 the component registers 28, 29, 30, and 31, for example, as percentage values 0.11; 0.02; 0.06; and 0.00.

In the assumed example, the lower portion of the matrix register 26 on completion of the matrix carries "zeros" in the 15 rows designated for I1, I2, and I3 and an indication of 100 percent in the row designated by the ingredient I4. That is, as I4 represents, "rolled barley" in the assumed example, and as "rolled barley" is 100 percent "rolled barley," the component register 32 carries a value of 100 percent.

The details of filling the component registers comprising the 20 matrix register 26 are set forth below; however, the control operations by the formulation specifications (registered in the right-hand columns of the matrix register 26) is to be appreciated as an important aspect hereof. It is also noteworthy at this time, that the data is developed in the system of FIG. 4, 25 element by element moving along one row at a time from column to column.

Access to and from the specific component registers (seven 30 bits) in the matrix register 26 is provided through address units. The somewhat distinct two columns 24 and 25 of component registers at the right side (as depicted) of the matrix register 26 invariably receive the specifications of the desired formulation and are separately accessed by a row address unit 34. During "unit" operations the bits 2-15 of the input words 35 are received in these component registers. Specifically the bits 9-15 pass into the rightmost column 25 while bits two to eight move into the next column to the left, column 24, as represented in FIG. 4.

The remainder of the component registers in the matrix 40 register 26 are separately and individually accessed by a column address unit 36 and a row address unit 38 functioning in combination. Specifically, the contents of the column address unit 36 designates the column into which data signals representative of a "percentage" are registered, while the row address unit 38 designates the row. Of course, the physical form of the matrix register 26 as well as the address units 34, 36, and 38, 45 may vary considerably.

In one form, the matrix register 26 may comprise a logical 50 array of magnetic core storage while the address units 34, 36, and 38, comprise address registers therefor. As schematically depicted in FIG. 4, the row address unit 34 is indicated by a dashed line 40 to control a contact 42 for addressing the right-hand component registers (columns 24 and 25). Somewhat similarly, a contact 44 is indicated to be controlled by the 55 units 36 and 38 by means of a dashed line 46 to address the other component registers. Although this form of representation is deemed to be somewhat simpler of presentation, it is to be understood that the electronic analogy thereof (as well known in the prior art) would be utilized in conjunction with a magnetic core storage system.

The operation of the system of FIG. 4 involves several 60 distinct phases which are manifest by timing signals that are provided from a timing unit 50. The timing signals provided by the unit 50 are summarized by the following chart:

Timing Signal	Initiated By	Function
t1:	Manually.	Load two component registers of right-hand column of matrix register with formulation specifications.
t2:	Manually or on completion of a phase t4 and a row.	Place a nutrient N in operative location.
t3:	Passage of a set period of t2 or	place an ingredient I in an address location to obtain

- t4: a completion of a phase t4.
Passage of a set period of t3.
- t5: Completion of the matrix.
- signal representations of the components thereof. Compare particular nutrient N with components of a specified ingredient.

In addition to the timing signals set forth above, the following signals are also developed within the system of FIG. 4.

Signal	Initiated By
S1:	A binary signal indicating a switch closure.
S2:	A binary signal indicating a switch closure.
H:	A binary signal indicating a "hit" in comparing nutrient N with component values of an ingredient or conclusion of a comparative test.
NN':	A binary signal indicating that no ingredients remain untested.
NN'':	A binary signal indicating that no nutrients or ingredients remain untested.

The timing signals t1 through t5 may be specified logically in view of the above as follows:

$$\begin{aligned}
 t1 &= S1 \\
 t2 &= S2 + (t4 \cdot H \cdot NI') \\
 t3 &= (t2 \cdot \text{time}) = (t4 \cdot H \cdot NI') \\
 t4 &= t3 \cdot \text{time} \\
 t5 &= t4 \cdot H \cdot NI' \cdot NN'
 \end{aligned}$$

In view of the above preliminary description of the system of FIG. 4, a complete understanding thereof may now best be accomplished by assuming certain initial conditions and objectives and explaining the operation of the system to accommodate such objectives while introducing other structural elements of the system as the explanation proceeds. Accordingly, assume that the nutrients of a particular desired formulation have been identified as nutrients N1 through Nn of which nutrients N1 through N4 will be here considered as exemplary. Additionally, assume that potential ingredients for a desired formulation have been identified as ingredients I1 through In (I1 through I4 here). As indicated, the nutrients N1 through N4 and the ingredients I1 through I4 will be considered with reference to the system of FIG. 4; however, as suggested, the system would normally accommodate substantially greater numbers.

The initial phase of operation involves loading the nutrients and ingredients into the component registers at the right side in columns 24 and 25 of the matrix register 26. This operation is performed manually (or may be under automatic control) during a timing interval defined by the high value of binary timing signal t1 provided from the timing unit 50. The interval of the signal t1 is initiated by the closure of a switch S1 (lower left) to provide a high signal to a specific input of the timing unit 50. Thereafter, the timing unit 50 continues to provide the signal t1 high until a switch S2 is closed (manually) thereby initiating the timing interval indicated by the signal t2.

During the interval of signal t1, binary code words as illustrated in FIG. 3 are provided in the input register 20 for transfer in sequence into the two columns 24 and 25 at the right-hand side of the matrix register 26. The code words occupy the two right columns 24 and 25 of component registers in the matrix register 26 and are transferred into such component registers during a plurality of individual operations.

Assuming a code word in the input register 20 identifying a nutrient N1 (and a minimum percentage thereof) a switch 52 (upper left) is closed to provide a qualifying signal to an AND-gate 54 to enable the contents of the register 20 to pass to the contact 42. During such an interval, the row address unit 34 receives an address number "one" through an AND-gate 56 from a nutrient-ingredient counter 58 which was set to "one" in the prior operation. That is, as described in detail below, the counter 58 tallies the code words registered in the matrix register 26.

The gate 56 (supplying the current number registered in the counter 58 to the address unit 34) is qualified by the timing signal t1. Consequently, as the initial word (nutrient N1) is under consideration, and the counter 58 is set at "one," and the address unit 34 is controlled to register the signal-represented word N1 (14 bits) received through the contact 42 in the last two columns 24 and 25 of row "one" (uppermost) of the matrix register 26.

The nutrient-ingredient counter 58, as indicated, is cleared by the operation-complete signal t5 and is stepped with each closure of the switch 52 through one of the AND-gates 60 or 62 and a connection gate 64. The gate 60 is qualified each time a "nutrient" word is entered in the system while the gate 62 is qualified each time an "ingredient" word is entered in the system. Specifically, the gate 60 is qualified by the negation of the first bit of the code word in register 20 while the register 62 is qualified by the true bit. These gates are additionally qualified by the timing signal t1 and the signal resulting from the closure of the switch 52. The gate 62 also drives an ingredient counter 68. Thus, ingredients and nutrients are distinguished. The counters, 58 and 68, may comprise step counters as well known in the prior art. Thus, as the counter 58 advances and additional code words are provided, they are registered in the last two columns 24 and 25 in advancing rows (top to bottom) of the register 26.

Recapitulating, individual code words representative of individual ingredient specifications are initially registered in the input register 20 then transferred, in row order, to the component registers in the last two columns 24 and 25 of the matrix register 26. Concurrently, the individual nutrients are tallied in the step counters 58 and 68.

Subsequent to entering the nutrient-specification code words, the ingredient-specification code words are similarly entered. That is, code words in accordance with FIG. 2, (indicative of potential ingredients for a formulation) are entered in the input register 20 and transferred in sequence to the rightmost columns 24 and 25 in the matrix register 26. Specifically, the percentage limitation of the ingredient's presence is specified in the second-to-right column, and the identification of the ingredient (along with an indication of minimum or maximum) is registered in the extreme right column. It is emphasized that each potential ingredient must be listed in accordance with the system thereof. Again, the row address unit 34 is incrementally driven by the nutrient-ingredient counter 58 to insert the code words in progressively advanced rows of the matrix register 26, and ingredients are counted in the counter 68.

Upon the complete registration of all the signal-represented nutrient and ingredient specifications, the switch S2 is closed (manually) advancing the timing unit 50 to provide the timing signal t2 in a high state. During the first interval, while the signal t2 is high, the first nutrient N1 (six bits) is transferred into a compare register 72 (lower right). Specifically, the row address unit 34 (now instructed to "read" by signal t2) receives signal indications for the numeral "one" (indicating the first row) through an AND-gate 74 from a step register 76 (upper right). The step register 76 is cleared by the signal t1 and is stepped by the signal t2. Consequently, initially, the contents of the register is "one" which is supplied through the AND-gate 74 and the connection gate 80 to the row address unit 34.

Previously, the row address unit received the signal t1 to command "write" operation; however, during the instant interval, the unit 34 receives the signal t2 to command "read" operations. Accordingly, the first nutrient N1 is provided from the matrix register 26 through the contact 42 and an AND-gate 71 to the comparison register 72. This operation requires a specific interval of time, after which the timing unit 50 automatically halts the provision of signal t2 high and initiates the high interval of binary signal t3.

During the interval when the signal t3 is high, the signal-represented ingredient I4 (six bits) is transferred from the matrix register 26 through the contact 42 and an AND-gate 84

to the address register 86 in an ingredient characteristic storage unit 88. Specifically, during the interval t_3 , the row address unit 34 (in a "read" mode) is driven through a subtractor 85, and AND-gate 90 from the nutrient-ingredient counter 58, which specifies the lowest (as shown) occupied row in the matrix register 26. The subtractor 85 also receives the contents of a register 102 which was cleared to "zero" at t_1 of the previous operation.

Accordingly, the signal-represented ingredient I_4 passes through the contact 42 and the AND-gate 84 to be received in the address register 86. That operation requires a consistent time interval after which the timing unit 50 provides the signal t_3 low and the signal t_4 high.

During the interval defined by the timing signal t_4 , the components of the ingredient identified (currently I_4) are provided from an address-specified location in the storage unit 88 to a comparator 92 for comparison with the nutrient N_1 which is held in the register 72. Specifically, for example, if the nutrient under consideration is "protein," then the code representation for "protein" is registered in the six-bit register 72. During the interval of the signal t_4 the storage unit 86 is driven by the signal t_4 to provide a series of code words including the ingredient (with a distinction bit) followed by its nutrient components; for example, the code-represented data might be as follows:

	Components	Percent	Representative signals
Address: 101101	Molasses.....	100	(1101101 1100100)
	Moisture.....	25	(011000 0011001)
	Protein.....	4	(100111 0000100)
	Calcium.....	1	(101011 0000001)
	Ash.....	10	(001010 0001010)
		:	
Address: 010110	Rolled barley.....	100	(1010110 1100100)
	Moisture.....	10	(010100 0001010)
	Protein.....	11	(100101 0000101)
	Fat.....	2	(110001 0000010)
	Fiber.....	6	(011110 0000110)
	Ash.....	1	(101011 0000001)
		:	

Specifically each word is represented by a seven-bit code (seventh bit "one") as is the percentage of its presence. That is, the ingredient and nutrient words include six binary bits plus an identifier bit in the most significant bit location ("1" = ingredient, "0" = nutrient) while the percentage codes comprise seven bits as illustrated above.

Upon the occurrence of the comparator 92 detecting a coincidence between the six bits of a nutrient code from the unit 88 and the nutrient code in the register 72, a high signal H appears in the conductor 94 for an interval of seven clock pulses of the storage unit 88. During that time the signal-represented percentage value of the nutrient is supplied from the storage unit 88 through an AND-gate 96 to be recorded in the first row, first column of the matrix register 26 as specified by the column address unit 36 and the row address unit 38.

The characteristic storage unit 88 may comprise any of a variety of units as well known in the art, including a disk storage unit substantially as shown and described in U.S. Pat. No. 3,503,060 (Direct Access Magnetic Disk Storage Device). Accordingly, the unit 88 has a specific operating time in accordance with its inherent cycle. Thus, during the interval as required to accommodate the signal-represented percentage value (seven bits) the AND-gate 96 is qualified to transfer such percentage value into the component register of the matrix register 26 as indicated by the column address unit 36 and the row address unit 38.

The column address unit 36 is controlled by an ingredient step register 102 which is cleared to "zero" by the timing signal t_1 and advanced to "one" by the signal H . Accordingly, during the initial phase of operation, the step register 102 passes a numerical representation of "one" to the unit 36 to specify the first column of the matrix register 26.

The row address unit 38 is controlled by the step register 76 (upper right) which is initially cleared (by signal t_1) then advanced to "one" by the signal t_2 , to specify the first row in the matrix register 26. Accordingly, the initial entry is in column one, row one.

If the comparator 92 detects a similarity, the signal H also is supplied to a delay circuit 104, the output of which is applied to the timing unit 50 to terminate the interval t_4 and reestablish the interval t_3 . The delay circuit 104 also receives 10 an input from a detector 106 as an alternate source of the signal H , which detects an "end" code provided from the storage unit 88 to indicate that all the components of a specific ingredient have been supplied from the unit 88. Thus, either upon the occurrence of a favorable comparison (hit) or 15 a completion of the file with no comparison, the signal H is supplied through the delay circuit 104 to terminate the interval of timing signal t_4 and, at the present stage, reestablish the interval t_3 .

Recapitulating, during the first interval defined by the timing signal t_4 , any percentage component of the nutrient N_1 that is present in the ingredient I_4 is entered at the location of column one and row one in the matrix register 26. If, for example, the ingredient I_4 is "rolled barley," and the nutrient N_1 is "protein," a percentage of 11 percent will be entered. 25 Alternatively, if the nutrient N_1 were "fat," no value would be entered in the identified component register 28, because "rolled barley" contains essentially no "fat" and no coincidence would occur.

During the second interval of the timing signal t_3 , the next 30 ingredient I_3 in reverse sequence is transferred into the address register 86. That is, as indicated, after the first operation is complete, the timing unit terminates the signal t_4 to again provide the signal t_3 at a high level. However, during the interval of the timing signal t_4 , the step register 102 was advanced 35 to a count of "one" which number is now supplied to a subtractor 85 along with the signal-represented contents of the nutrient-ingredient counter 58. As a consequence, the output of the subtractor 116 is the total list of nutrients and ingredients, less "one" which provides a number designating the row 40 containing the ingredient I_3 in the matrix register 26. Specifically, during the interval t_3 , the output from the subtractor 116 is supplied through the AND-gate 90 to the row address unit 34 which in turn controls the output from the matrix register 26 to provide a signal-represented ingredient 45 I_3 through the contact 42 and the AND-gate 84 to be received in the address register 86.

This transfer occurs during the preestablished interval of t_3 , after which the time signal t_3 is automatically terminated to 50 initiate the interval of the timing signal t_4 . During the interval of t_4 , another comparison is performed in search of components of the nutrient N_1 in the ingredient I_3 as addressed by the ingredient-representative signal of ingredient I_3 .

As previously explained, a coincidence results in a registered value while the failure of a coincidence to occur 55 simply terminates the interval of the timing signal t_4 . In the event that a coincidence is detected, the percentage detected is registered in the component register located in the first row, second column of the matrix register 26. That component register is specified because the ingredient register 102 advanced by the signal H to provide the number "two" to the column address unit 36 while the nutrient step register 76 continues to provide the number "one" to the row address unit 38.

In this manner, the system proceeds to develop a series of 60 percentage values representative of the presence of the nutrient N_1 in the various ingredients I_4 through I_1 registering such percentage values across the top row of component registers in the matrix register 26. As the operation progresses, it 65 may be seen that a matrix is developed in the matrix register 26 specifying the nutrient components of the various ingredients. Specifically, the format of the developed matrix is illustrated in the following chart:

75	14 30	13 10	12 05	11 04	N1

60	05	00	02
00	09	42	12
01	41	16	01
00	00	00	100
00	00	100	00
00	100	00	00
100	00	00	00

When the first row (or following rows) of the matrix is completed, the contents of the ingredient register 102 is stepped to equal the contents of the ingredient counter 68 (e.g., a count of four). Upon such an occurrence, a signal NI' is formed by the comparator 118 indicating that each of the ingredients I4 through I1 have been considered and the first row of the matrix is complete. The signal NI' from the comparator 118 is applied to the timing unit 50 to terminate the interval of the timing signal $t4$ and again establish the timing interval of signal $t2$. As indicated below, during the interval of $t2$, a fresh nutrient is placed in the nutrient comparison register 72. On the occurrence of the signal $t2$, the step register 76 (upper right) is advanced to register the number "two" which number is placed in the row address unit 34 through the AND-gate 74 during the interval of the timing signal $t2$. Therefore, the row address unit 34 then specifies the nutrient N2 (located in the second column) in the matrix register 26 to be transferred through the contact 42 and the AND-gate 71 to the nutrient comparison register 72.

Concurrently with the above, the ingredient register 102 is reset by the timing signal $t2$ to initiate another cyclic scanning through the ingredients I4 through I1 so as to register the component nutrients of these ingredients in the second row of the matrix register 26.

As the operation of the system continues, the matrix is developed row by row in the matrix register 26 and in time the ingredient I1 is again placed in the compare register 72. Thus, in accordance herewith, the entire matrix is generated in the component registers defined in columns and rows, each identifying ingredients.

Referring to the above chart and to FIG. 1, it is to be noted that the component registers in the lower portion of the matrix contain values of either 100 percent or 0. Specifically, for example, if an ingredient is "rolled barley," it constitutes 100 percent "rolled barley." On the contrary, if an ingredient is "cane molasses," it constitutes absolutely no "rolled barley." The lower portion of the matrix is developed just as the upper portion of the matrix is developed, by a sensing of coincidence between the content of the register 72 and the codes provided from the characteristics storage unit 88; however, the ingredients are identified as such by a seventh bit that is provided to the comparator 92 from a comparator 123 which senses that the nutrients N1 through N4 rows have been completed by reason of the contents of the register 76 coinciding to that of the counter 58 less that of the counter 68. That is, the six-bit codes from component registers in column 25 that represent ingredients, are supplemented by an additional seventh bit from the comparator 123 to identify the code as an ingredient. Consequently, when the addressed section of the storage unit 88 provides the seven-bit code word for that ingredient a hit is detected producing the signal H high and entering the value of 100 in the appropriate component register.

When the last row of the matrix register 26 is complete, the contents of the step register 76 is stepped to exceed the contents of the nutrient-ingredient counter 58. That condition is detected by a nutrient comparator 121 which initiates the signal NN' to provide the signal $t5$ from the timing unit 50. This signal indicates the completion of the matrix in the matrix register 26 and qualifies an AND-gate 122 (comprising a parallel gang gate) to supply the entire contents in positional

significance, from the matrix register 24 for processing by a linear-program computer.

Thus, it may be seen that the system hereof operates effectively to develop a nutrient-ingredient matrix for use by a linear-programming computer, essentially entirely under the control of a feed-formulation specification as provided in the right-hand column of the matrix register. The system is economical and relatively simple in operation.

Of course, the system hereof may be variously utilized to formulate ingredient-nutrient matrices and various alternative structures may be employed. Accordingly, the scope hereof is to be determined in accordance with the following claims.

What is claimed is:

1. A system for providing nutrient and ingredient data in a matrix format, for a linear-programming computer, to accomplish an objective feed formula comprising:

a matrix register means including a plurality of component registers with row and column significance;

means for registering signal-represented formula requirements, including all specific nutrients and all specific ingredients, in said matrix register as one column therein; means for counting said ingredients and said nutrients registered in said matrix register, to specify the columns and rows of said matrix;

storage means for registering a plurality of ingredients that may be specified, along with the component nutrients thereof;

means for selectively registering, as other columns of said matrix, in said matrix register means, specified nutrients of said ingredients along with indications of said ingredients; and

means for reading said matrix out of said matrix register means with column and row significance.

2. A system according to claim 1 wherein said means for counting includes a first counter for counting each of said specific ingredients values and said specific nutrients values.

3. A system according to claim 2 further including a second counter for counting only one of said values.

4. A system according to claim 1 wherein said means for selectively registering includes means for comparing signal-represented component nutrients of an ingredient with a specific signal-represented nutrient to register values thereof upon the occurrence of a coincidence.

5. A system according to claim 4, wherein said means for selectively registering further includes means for registering a signal-represented nutrient during an interval of comparison with nutrient components of each specific signal-represented ingredient to register values in said matrix register means.

6. A system according to claim 5 wherein said means for selectively registering further includes means for designating said individual component registers in said matrix register means in a predetermined order along each row in sequence.

7. A system according to claim 1, including a timing control means and further including means connected to said means for counting to control said timing control means to sequence the operation of said means for selectively registering.

8. A system according to claim 7 wherein said means for counting includes a first counter for counting each of said specific ingredients values and said specific nutrients values.

9. A system according to claim 8 further including a second counter for counting only one of said values.

10. A system according to claim 9 wherein said means for selectively registering includes means for comparing signal-represented component nutrients of an ingredient with a specific signal-represented nutrient to register values thereof upon the occurrence of a coincidence.
